Primary Examiner—Dominic Simone

(57) **CLAIM**

The ornamental design for a boot-tree, as shown and described.

DESCRIPTION

FIG. 1 is a front elevational view of a boot tree, showing our new design;

FIG. 2 is a side elevational view thereof, the opposite side being identical;

FIG. 3 is a rear elevational view thereof, on a reduced scale;

FIG. 4 is a side perspective view of FIG. 3 in a partial folded position;

FIG. 5 is a side perspective view of FIG. 4, in a further folded position; and,

FIG. 6 is a perspective view of a FIG. 3 folded in a position for use.
